United States Patent

Des. 236,464
Patented Aug. 26, 1975

236,464

ANGLING ARROW

Joseph P. Mole, Indianapolis, Ind.
(P.O. Box 50030-A, Castleton, Ind. 46250)

Continuation-in-part of design application Ser. No.
313,107, Dec. 7, 1972. This application Mar. 1,
1974, Ser. No. 446,649

Term of patent 14 years

Int. Cl. D22—03

U.S. Cl. D22—12

FIG. 1 is a side elevation view of an angling arrow showing my new design;

FIG. 2 is a perspective view of the rear portion of said arrow; and

FIG. 3 is a perspective view of the forward portion of said arrow and the ferrule at the forward end.

This application is a continuation-in-part of my application Ser. No. D. 313,107, filed Dec. 7, 1972.

I claim:

The ornamental design for an angling arrow, as shown.
